EARTH FORMATION SAMPLING APPARATUS

Boris Schneersohn, Paris, France, assignor to Societe de Prospection Electrique Procedes Schlumberger, Paris, France, a corporation of France

Application April 25, 1955, Serial No. 503,541

Claims priority, application France May 3, 1954

4 Claims. (Cl. 255—1.4)

The present invention relates to apparatus for obtaining samples of the contents of earth formations traversed by a well. More particularly, it has to do with new and improved apparatus of this character which enables uncontaminated samples to be obtained regardless of the relative pressure conditions in the formations and in the bore hole.

The copending application Serial No. 386,279, filed October 15, 1953, for "Apparatus for Sampling Fluids in Geological Formations" discloses apparatus for obtaining samples of fluids in geological formations, comprising a hollow projectile adapted to be projected against the formation (sidewall of the bore hole) from which a sample is desired and attached in a known manner by cables or similar means to the device which ejects it. This projectile has a forward cap member adapted to form a fluid-tight fit with the well wall. The cap member is provided with a frangible closure adapted to be destroyed on impact to afford access for the formation fluid to a sample receiving chamber in the projectile. After the fluid receiving chamber is filled, a retaining valve closes and remains closed while the projectile is brought back to the surface of the earth.

The retaining valve inside the projectile is designed to function in response to differential pressure, so that as soon as a sample of the formation fluid has been received in the sample receiving chamber inside the projectile, the valve closes. Thereafter, on account of the differential pressure being exerted on its head, it maintains sufficient force to prevent it from being subsequently opened during the return of the equipment to the surface.

In a typical embodiment described in the aforementioned application, the retaining valve has a movable head in the chamber provided to receive and retain the collected fluid sample. In the valve head is formed a cylindrical bore in which is snugly received a fixed piston member on which the valve head can slide relatively to the body of the projectile. Hence, the pressure exerted on the head of the valve by the fluid sample in the chamber will have the effect of pressing the valve on its seat while overcoming the action of the difference in pressure exerted between the inside and outside of the chamber. Actually, this pressure is proportional to the difference between the pressure existing in the interior of the chamber containing the fluid sample and atmospheric pressure, or a pressure on the order of atmospheric pressure, existing in the interior of the cylindrical bore in which the piston is received. While this apparatus is capable of giving good results, it is most effective in locations where the fluid pressure in the formations to be sampled is not too much different from the fluid pressure in the bore hole.

It is an object of the present invention to provide new and improved sample taking apparatus of this general character which affords a perfect seal for the chamber containing the stored liquid sample, regardless of the

2

relative conditions of pressure existing in the hole and in the earth formations.

This and other objects and advantages of the invention are attained by utilizing the difference between the pressure existing outside of the sample receiving chamber and atmospheric pressure (or a pressure of the same order as atmospheric pressure) as the differential pressure creating the force serving to press the valve on its seat, instead of using the difference between the pressure inside the sample receiving chamber and atmospheric pressure for this purpose, as in the earlier device described above. It follows then, that the greater the pressure existing outside the sample receiving chamber (i. e., in practice, the mud pressure) the greater will be the force caused by the differential pressure. Hence, by appropriately designing the surfaces where the different pressures acting on the valve are exerted, the force exerted on the head of said valve can be made sufficient to insure absolute airtightness no matter what conditions of pressure exist. It is even possible to lower the equipment to bore hole levels where the pressure of the mud is considerably higher than at the place where the samples were taken, without any reopening of the valve.

In a preferred form of the invention, the head of the retaining valve carries a piston which is slidably received in a cylindrical bore in a member maintained in fixed relation to the projectile. Further, the piston is disposed outside of the sample receiving chamber in which a fluid sample has been collected, so as to be acted upon by the pressure outside of the chamber.

The invention may be better understood from the following detailed description of a representative embodiment, taken in conjunction with the accompanying drawings in which:

Fig. 1 is a view in transverse section through a bore hole drilled into the earth, showing sample taker apparatus according to the invention positioned therein; and

Fig. 2 is a view in longitudinal section through a sample taker projectile constructed according to the invention.

Referring now to Fig. 1, a bore hole 10 which usually contains water and mud 11 is shown traversing earth formations 12, which may comprise, for example, sand filled with fluid (liquid or gaseous), a sample of which is desired. Within the bore hole 10 is positioned lateral sample taking gun apparatus 13 in which a chamber 14 is formed. The chamber 14 constitutes a gun barrel for a sample taking projectile 15 which may be fired against the side wall of the bore hole 10 upon ignition of a powder charge 16 in the conventional manner.

While only a single chamber 14 and projectile 15 are shown in the figure in the interest of simplicity, actually the sample taking apparatus 13 is provided with a plurality of superimposed chamber or gun barrels, each of which contains a sampling projectile 15. The sampling projectiles 15 are connected by cables 17 to the body of the sample taking apparatus 13 so that when the latter is raised to the surface, the sampling projectiles 15 are pulled along with it by the cables 17 and are also brought to the surface. This arrangement is conventional in lateral bore hole sampling devices.

As shown in Fig. 2, the sampling projectile 15 comprises a hollow cylindrical body formed of two parts 18 and 19, threaded one to the other to facilitate fabrication and assembly. Within the body is a sample receiving chamber 20 which is adapted to receive a sample of the fluid through a port 21. The port 21 is normally closed by a retaining valve having a head member 22 provided with an upper surface 23 having a groove 24 in which is fitted a sealing ring 25. The sealing ring 25 is adapted to be pressed against the forward side wall of the chamber 20 so as to form a fluid-tight joint.

The head member 22 is formed with a cylindrical surface 26 which is slidably mounted in the port 21. The cylindrical surface 26 is pierced laterally by holes 27. Further, it is formed integral with a rod 28 carrying at its upper extremity a piston 29 having a lateral groove 5 30 for insertion of a sealing ring 31. The piston 29 is adapted to slide in a cylindrical bore 32 formed in a member 33 threadedly secured in a throat portion 34 communicating with the port 21. The member 33 is provided with orifices 35 to permit the passage of the 10 fluid therethrough.

Formed on the part 18 is a stop 36 which serves to limit the movement of the valve 21 in the chamber 20.

On the forward end 37 of the body 19 there is shrink fitted a cap member 38, also of cylindrical shape, a cavity 15 39 being provided between the cap member 38 and the forward end 34 of the body 19. A sealing ring 40 insures fluidtightness between the forward end 34 and the cap member 38.

The cap member 38 is made of a relatively soft metal such as pure aluminum, for example, and it has formed therein an orifice 41 closed by a frangible closure member 42 which is integral therewith. The cap member 38 is of relatively large outside diameter and its forward portion 43 has a cross-section which is, preferably, a truncated cone with a wide angle at the apex. The forward portion 43 of the cap member 38 has a groove 44 formed therein in which a sealing ring 45 is received.

In operation, the sample taker 13 (Fig. 1) is lowered into the bore hole 10 to the desired level, and the powder charge 16 is set off to project sample taking projectile 15 in the known manner against the side wall of the bore hole. The sample taking projectile 15 penetrates relatively lightly into the bore hole side wall, as shown in dotted lines in Fig. 1, the depth of the penetration depending on the nature of the wall material. As a result of the violent impact between the projectile 15 and the wall of the bore hole, the front portion 43 of the cap member 38 is deformed and is to some extent molded into the formation which constitutes the side wall of the bore hole, forming a tight joint with the side wall. This effect is considerably increased through the presence of the groove 44 and the sealing ring 45. At the same time, under the outside pressure exerted on the closure 42, the latter shears and there follows an inrush into the chamber 46 of the substance (sand imbibed with fluid, for example) forming the side walls of the boring.

Because of the tight joint between the forward face of the cap member 38 and the wall of the bore hole, the bore hole liquid 11 cannot reach the orifice 41. Indeed, substantially only the materials derived from the formation itself, ever enter the chamber 46. The substances which have penetrated into this chamber under the effect of the strong pressure they exert, push back the valve 22, which, guided by the piston 29 and the surface 26 slides until it is brought to rest by the stop member 36. In this position, the fluid freely passes into the chamber 20 through the orifices 27 until the chamber 20 is completely filled.

The recoil movement of the valve 22, which is limited by the stop member 36, creates a vacuum in the cavity located between the top of the piston 29 and the bore 32, so that when the chamber 20 is filled, the valve 22 closes again under the effect of the pressure exerted in the chamber 46 on the under side of the piston 29. 60 When the projectile is pulled out of the bore hole side wall, the pressure of the bore hole liquid is applied to the under side of the piston 29. The differential effect between the pressure of the bore hole liquid and the pressure inside the chamber between the top of the piston and the bore 32 is sufficient in any state and whatever the conditions, as has been previously stated, to keep the valve 22 tightly pressed on its seat, preventing any inrush of bore hole liquid to the inside of the chamber 20.

It should also be noted that fluid tightness is always insured by the ring 25. Further, the slide valve arrangement formed by the cylindrical portion 26 and the port 21 insures the lower centering of the valve, and, above all protects the ring 25 when there is an inrush of fluid at great velocity into the chamber 20, it being understood that this ring is widely separated from the inside front wall of the projectile 15 which constitutes its seat, when the fluid begins to pass through the orifices.

After the sample taker 13 has been brought to the surface, the substances in the cavity 20 may be collected in any suitable manner.

Of course, numerous variations can be made in the typical embodiment described above without departing from the scope of the invention. In particular, the bore 32 in Fig. 2 might be formed in the valve head with the piston being carried by the member 33, provided that the piston cavity assembly is always situated outside the chamber 20 in which the fluid samples are collected. The invention, therefore, is not to be restricted to the specific form shown by way of illustration, but comprehends all such modifications as come within the scope of the following claims.

I claim:

1. Apparatus for sampling the fluid content of geological formations and the like comprising a hollow tubular projectile adapted to be projected into a formation, means forming a temporary closure for one end of said projectile, means forming a transverse partition in said projectile and cooperating with the other end portion of said projectile to form a fluid storage chamber, means forming an orifice in said partition, valve means normally closing said orifice, tubular skirt means on said valve means and slidably mounted in said orifice, said skirt means having laterally directed openings formed therein, cooperating piston and bore means carried by said valve means and by said projectile and bounding a confined space, said piston and bore means being moved relative to one another when said valve means is opened to enlarge said confined space and being moved relative to one another when said valve means is closed to contract said confined space, and said cooperating piston and bore means being responsive to fluid pressure outside of said chamber for developing force tending to close said valve means.

2. In apparatus for sampling the fluid content of geological formations and the like which comprises a hollow tubular member closed at one end and having an orifice at its other end and valve means for closing said orifice, the combination of tubular skirt means on said valve means slidably mounted in said orifice and having laterally directed apertures formed therein, said apertures providing free communication between the interior and exterior of said tubular member when said valve means is opened, a support member mounted in fixed relation to said tubular member in the vicinity of said orifice, cooperating piston means and bore means carried by said valve means and by said support means and bounding a confined space, said piston means and bore means being moved relative to one another when said valve means is opened to enlarge said confined space and being moved relative to one another when said valve means is closed to contract said confined space, and said cooperating piston means and bore means being responsive to fluid pressure outside said tubular member for developing a force tending to close said valve means.

3. In apparatus for sampling the fluid content of geological formations and the like, the combination of a hollow tubular member closed at one end and having a port at its other end tapering outwardly to an opening of larger size than the port, valve means in said tubular member for closing said port, tubular skirt means on said valve means slidably in said port and having laterally directed openings formed therein providing free communication between the interior and exterior of said tubular means when said valve means is opened, a sup-

port member mounted in said opening in said tubular member having passage means therein providing access to said port, cooperating piston and bore means carried by said valve means and by said support member and bounding a confined space, said piston means and bore means being moved relative to one another when said valve means is opened to enlarge a confined space and being moved relative to one another when said valve means is closed to contract said confined space, said cooperating piston means and bore means being responsive to fluid pressure outside said tubular member for developing a force tending to close said valve means, and a cap member tightly fitted at said other end of the tubular member, said cap member being formed with a frangible closure and cooperating with said other end of the tubular member to form a chamber in front of said tubular member.

4. In apparatus for sampling the fluid content of geological formations and the like, the combination of a hollow tubular member closed at one end and having a port at its other end tapering outwardly to an opening of larger size than the port, valve means in said tubular member for closing said port, sealing means for said valve means, tubular skirt means on said valve means slidable in said port and having laterally directed openings formed therein providing free communication between the in-

20
25

terior and exterior of said tubular means when said valve means is opened, a support member mounted in said opening in said tubular member having passage means therein providing access to said port, cylinder means carried by said support member, piston means carried by said valve means and slideable in said cylinder means in fluid tight relation thereto, said piston means being moved outwardly and inwardly of said cylinder means when said valve means is opened and closed, respectively, said piston means being responsive to fluid pressure outside of said tubular member for developing force tending to close said valve means, stop means in said tubular member limiting opening movement of said valve means, and a cap member tightly fitted at said other end of the tubular member, said cap member being formed with a frangible closure and cooperating with said other end of the tubular member to form a chamber in front of said tubular member.
